CLAIM

The ornamental design for a shoe, as shown and described.

DESCRIPTION

FIG. 1 is a front perspective view of a shoe showing my new design;

FIG. 2 is a top view thereof; and,

FIG. 3 is an opposite side front perspective view thereof. The contrast in shading between the three shaded areas represents a contrast in appearance only. The broken lines immediately adjacent to the sides of the shaded areas define the bounds of the claimed design and form no part thereof. The broken lines depicting the remainder of the shoe form no part of the claimed design.
